UNITED STATES PATENT OFFICE.

CHARLES RAUCH, OF ST. LOUIS, MISSOURI.

HAT-PIN CLASP.

1,251,417.

Specification of Letters Patent. Patented Dec. 25, 1917.

Application filed August 31, 1915. Serial No. 48,294.

To all whom it may concern:

Be it known that I, CHARLES RAUCH, a citizen of the United States, residing at St. Louis, in the county of St. Louis and State of Missouri, have invented new and useful Improvements in Hat-Pin Clasps, of which the following is a specification.

This invention relates to an improved combined hat pin clasp and pin protector.

10 The invention has for its object to produce a simple and improved device which will serve as a point protector and also as a clasp or fastener to hold the pin securely against withdrawal.

15 A further object of the invention is to produce a simple and efficient device which may be readily applied to the point and which may be readily withdrawn by a pulling action on a certain part of the device.

20 With these and other ends in view which will readily appear as the nature of the invention is better understood, the same consists in the improved construction and novel arrangement and combination of parts 25 which will be hereinafter fully described and particularly pointed out in the claim.

In the accompanying drawing has been illustrated a simple and preferred form of the invention, it being, however, understood 30 that no limitation is necessarily made to the precise structural details therein exhibited, but that changes, alterations and modifications within the scope of the claim may be resorted to when desired.

35 In the drawing,—

Figure 1 is a sectional elevation of the body member of the device.

Fig. 2 is a sectional view of the sleeve or housing.

40 Fig. 3 is a side elevation showing the body member with the spring applied thereto.

Fig. 4 is a sectional view showing the device complete.

Fig. 5 is a sectional view showing the device applied to a hat pin.

Corresponding parts in the several figures are denoted by like characters of reference.

The body member of the improved device comprises a bulb 15 having a shank 16 provided with a terminal flange 17, said shank being provided with a longitudinal bore 18 that extends within the bulb. The shank is provided with a longitudinal slot 19 extending from the flanged end in the direction 50 of the bulb 15. The body member is made of metal or other material possessing a high degree of inherent resiliency; the prongs *a* formed by the slot 19 will, therefore, be quite resilient.

The neck or shank of the device is surrounded by a coiled spring 20, one end of which abuts on the flange 17, while the other end of said spring initially abuts on the bulb 15, as will be best seen in Fig. 3. The spring is surrounded by a housing consisting of a tapering sleeve 21 having at its narrow end an inwardly extending flange 22, the edge of which is beveled, as seen at 23, to facilitate the entrance of a point of a hat pin. The wide end of the sleeve 21 is provided with an inturned bead or flange 24 which may be formed in some convenient manner after assembling the sleeve with the body member, and which forms an abutment for the inner end of the coiled spring 20.

In practice, the spring 20 abutting at one end on the flange 17 of the body member and at the other end on the flange 24 of the housing will force the latter in the direction 80 of the bulb 15, the parts being so proportioned that the tapering sleeve or housing will exert a compressing action on the prongs *a*. In order to apply the device it is grasped by the sleeve or housing 21, and 85 the point of the pin, as seen at 25, is inserted through the beveled aperture formed by the flange 22 at the narrow end of the housing, between the prongs *a* of the body member which is pushed against the tension 90 of the spring 20. The pin point will now enter the bore 18 between the prongs *a* until its reaches the bottom of said bore when further movement is impossible. Now, when the housing is released the tendency 95 of the spring 20 will be to restore the body member and the housing to their initial position, thereby causing the tapering end of the sleeve to exert a clamping action on the prongs between which the pin will thus 100 be securely held. The device, it will thus be seen, forms a pin protector and also a guard or fastening device which will prevent the withdrawal of the pin through the hat or other object engaged thereby. To remove the device the pin is grasped by one hand, and the bulb 15 is grasped by the other hand and pulled in an outward direction, thus compressing the spring 20 and moving the flanged end of the shank toward 105 the wide portion of the housing, permitting the prongs to expand, thereby releasing the

grasp on the pin and permitting the device to be readily removed.

As will be seen from the foregoing description, I have provided a device of simple, inexpensive and attractive construction which may be very readily applied or detached and which will be found thoroughly effective for the purpose for which it is provided.

10 Having thus described the invention, what is claimed as new, is:—

In a device of the class described, a body member comprising a bulb having a shank provided with a terminal flange, said body member being fashioned of resilient material and provided with a bore extending longitudinally through the shank into the bulb and with a slot bifurcating the shank to form clamping jaws having outwardly 20 extending flanges at their free ends, in com-

bination with a housing consisting of a sleeve of tapering form through its entire length, said sleeve surrounding the shank and having terminal flanges, the flange at the small end of the sleeve lying in the path 25 of the flanges of the clamping jaws and having a beveled edge to facilitate the entrance of the pin point; and a spring coiled loosely about the clamping jaws formed by the slotted shank, said spring abutting terminally, at one end on the flange at the other end of the sleeve and at the other end on the flanges of the clamping jaws to directly engage and actuate the same.

In testimony whereof I affix my signature 30 in presence of two witnesses.

CHARLES RAUCH.
